LAWSON P. KEACH, OF BALTIMORE, MARYLAND.

Letters Patent No. 86,165, dated January 26, 1869; antedated January 11, 1869.

COMBINED BOOT-JACK AND BLACKING-CABINET.

The Schedule referred to in these Letters Patent and making part of the same.

To whom it may concern:

Be it known that I, LAWSON P. KEACH, of the city of Baltimore, State of Maryland, have invented a certain new and useful Improvement for Combining with the ordinary Boot-Jack a Blacking-Cabinet, to contain the box of blacking and brush, and the whole so contrived as to be used, at pleasure, either as a boot-jack or stand to support the foot while blacking the boot or shoe on the same, the following being a full, clear, and exact description, reference being had to the accompanying drawing, which forms part of the specification.

My improvement has reference to the common board boot-jack, the space under which, at its usual and necessary elevation, (the rear part being raised to a level with the hollow end,) being economized by enclosing it on three sides, in the rear of the notch or hollow end, forming a box, which opens at said end to receive and enclose the brush when not in use; and on the top of said board, having thick-head nails, or other suitable prop, for the double purpose of sustaining the sole of the boot or shoe secure from slipping, while the upper is being blacked or polished on the foot, or for the placing of one foot to draw the boot from the other; and the bottom of said box is composed of sheet-metal, to afford sufficient space for the brush without too great an elevation of the boot-jack.

The remaining space under the hollow end of the top board or boot-jack is used as a place for the blacking-case when closed, in the following ingenious and novel manner:

The said blacking-case or box is so arranged with hinges as to swing out when the apparatus is required to be used for either of the above purposes, and opening at the right-hand side when blacking is required to be used therefrom.

The bottom part of said hinged box or blacking-case is a solid block, the thickness of which is half the height of the outside of the whole apparatus, and in the top surface of said block is carved or bored a round

space, of sufficient depth to contain an ordinary tin box of paste-blacking.

The top part of said case is also a solid block, the thickness of which fills the remaining height of space under the top or boot-jack board, and also has a cutting on its surface, similar to that in the bottom block, of sufficient depth to contain the cover of said tin box of blacking, for the convenience of holding water, or of working the brush with blacking to be applied to the leather.

Attached by a hinge to the top part of the herein-described case for the box of blacking, is a block, of the thickness and shape of the hollow or notch of the boot-jack, which, exactly fitting the hollow space, opens and closes into the same, and with the addition of a small projection of the sheet-metal bottom of the brush-box at the opening end, serves the purpose of a complete fastening to the whole cabinet, as well as giving the same a neat and finished appearance when closed; and also serves the purpose of elevating the upper part of the blacking-case, to make the cover level and firm with the box of blacking when open and in use, as above described.

I do not claim of itself the shape of the boot-jack board, or the box which supports it, which are common; but

I do claim—

1. The hinged case A, with a cavity in one part for the blacking-box and its cover, attached to the opposite part, so that it can be utilized, as and for the purposes set forth.

2. The combination and arrangement of the case A with the boot-jack B and brush-box C, as and for the purposes described.

In testimony whereof, I have hereunto subscribed my name, this 12th day of June, 1868.

LAWSON P. KEACH.
